FOREIGN PATENT DOCUMENTS

EP	436107	11/1990
FR	2682086	3/1992

Primary Examiner—Stella Reid*Assistant Examiner*—Mark Goodwin(74) *Attorney, Agent, or Firm*—Nelson Mullins Riley & Scarborough, LLP(57) **CLAIM**

The ornamental design for a container clip, substantially as shown and described.

DESCRIPTION

FIG. 1 is a perspective view of a container clip embodying the design of the present invention;

FIG. 2 is a right side elevational view of the container clip illustrated in FIG. 1, the left side elevational view being a mirror image of the right side elevational view;

FIG. 3 is a front elevational view of the container clip illustrated in FIG. 1;

FIG. 4 is a rear elevational view of the container clip illustrated in FIG. 1;

FIG. 5 is a top view of the container clip illustrated in FIG. 1; and,

FIG. 6 is a bottom view of the container clip illustrated in FIG. 1.
